DESIGN FOR A COMBINED FLOWER POT AND RECEPTACLE THEREFOR

James R. Starkweather, Rochester, N. Y.

Application August 5, 1948, Serial No. 147,962

Term of patent 3½ years

(Cl. D35—3)

To all whom it may concern:

Be it known that I, James R. Starkweather, residing at Rochester, in the county of Monroe and State of New York, have invented a new, original, and ornamental Design for a Combined Flower Pot and Receptacle Therefor, of which the following is a specification, reference being had to the accompanying drawing, forming part thereof.

Fig. 1 is a perspective view of a combined flower pot and receptacle therefor, showing my new design;

Fig. 2 is a top plan view of the flower pot;

Fig. 3 is a perspective view of the flower pot;

Fig. 4 is a perspective view of the receptacle; and Fig. 5 is a top plan view of the receptacle.

I claim:

The ornamental design for a combined flower pot and receptacle therefor, as shown.

JAMES R. STARKWEATHER.
